UNITED STATES PATENT OFFICE.

JAMES B. GIFFEN, OF SAN FRANCISCO, CALIFORNIA.

RIFFLE.

1,198,342.

Specification of Letters Patent. Patented Sept. 12, 1916.

Application filed July 8, 1914. Serial No. 849,769.

To all whom it may concern:

Be it known that I, JAMES B. GIFFEN, a citizen of the United States, residing in the city and county of San Francisco and State 5 of California, have invented certain new and useful Improvements in Riffles, of which the following is a specification.

In stationary riffles, the sand has a tendency to pack against the riffle slats, thus 10 destroying the efficiency of the riffle, as all "values" under such conditions cannot be retained. It has been proposed to give the riffle a slight vertical movement to overcome this condition, but such movement is 15 objectionable in that it gives an inertia movement to the "values" and precipitates them over the riffles whereby they are lost.

The object of my invention is to provide the riffle slats with an overhanging face which 20 is presented upstream, so as to form a pocket into which the "values" settle, and then give the riffle a lateral motion which causes the sand and other foreign materials to float off, leaving the "values" in the pocket; and 25 with this and other objects in view, my invention consists of the parts and combination of parts as will be more fully herein-after pointed out.

In the drawings, Figure 1 is a side elevation of an ore concentrator embodying 30 my invention; Fig. 2 is a longitudinal vertical section of the same parts, being in elevation; Fig. 3 is a transverse section on the line A—B, Fig. 1; Fig. 4 is a detail sectional view taken substantially on the line 35 C, D of Fig. 1. Fig. 5 is an enlarged detail view of the riffle; Fig. 6 is an enlarged detail view of an intermittent gear drive, and Fig. 7 is a perspective view of a riffle board, 40 parts being broken away.

The reference numeral 1 designates a suitable base, on which is mounted the frame 2.

3 is a driving pulley connected to a suitable source of power on the shaft of which 45 is a gear wheel 4 meshing with the gear wheel 5. The base 1 is provided with suitable slides 6, in which T-headed standards 7 are adapted to slide, said standards being 50 connected to the frame 2, so that by the mechanism hereinafter described, the frame 2 may be given a lateral reciprocation, but at the same time is held against any vertical movement by the T-head of the standards 7 fitting under the overhangs of the 55 slides 6.

The shaft 8 to which the gear 4 is keyed is provided with two cranks 9, to which are connected, respectively, pitmen 10, which in turn are connected to yokes 11 secured at 60 their upper ends to the frame 2 in any suitable manner.

11^a is a stub shaft connected to the hollow shaft 12 by means of a universal joint 13.

14 is a shaft, one end of which is movably mounted within the hollow shaft 12, so that there may be relative lengthwise movement between the shafts 12 and 14, as will be readily understood.

15 is a stub shaft connected to the upper end of shaft 14 by means of the universal joint 16.

17 is a beveled gear having a shaft 18 which passes transversely through the frame 75 2.

19 is a beveled pinion adapted to intermittently mesh with the beveled gear 17.

20 is a cam mounted on the shaft 15 and bearing on the central portion of the gear 80 17, so that the pinion 19 is intermittently moved out of and into engagement with the gear 17, the spring 21 tending to normally hold the cam into engagement with the face of the gear 17.

A belt 22 is mounted on the rollers 23 within the frame 2, said belt being provided with riffle slats 24, there being bottom pieces 25 on the belt between the slats.

26 is a feeding trough for gravel, sand, 90 ore and water, having its discharging end disposed about midway the length of the belt.

27 and 28 are auxiliary water discharging nozzles.

29 is a discharging chute positioned under the delivery end of the endless belt.

As more clearly shown in Fig. 5, the riffle slats 24 have overhanging edges or undercut faces 30, which are the upstream faces of the 100 riffle slats, the bottom portion 25 being spaced at one edge from the inclined face of the riffle slat 24 and inclined toward the vertical face of the next adjacent slat. The space between the bottom piece 25 and the 105 inclined face 30 constitutes a pocket 31, in which quick silver may be placed.

In Fig. 7, I have shown my invention embodied in a riffle board, in which the slats 32 are of the same construction as shown in 110 Fig. 5.

As stated, the overhang or inclined faces

30 of the ~~rim~~ slats are presented upstream. That is to say, the water flowing over the riffle strikes against the inclined faces, causing an eddy, which deposits the "values" 5 under the inclined faces so that the "values" gradually sink into the pockets 31 on the riffle, where they are held securely against loss.

By holding the riffle against vertical motion and at the same time reciprocating it laterally, the metallic particles settle down to and lie on the face of the table, or bottom if the riffle is made in the form of a tray, and remain practically motionless, but gradually work down the inclined faces of the riffle slat into the trap 31, if a trap is used, and are thus secured against loss by being washed over the riffle.

When the trap 31 is filled with mercury, 20 it serves as an amalgamator and as a retainer for those particles that will not amalgamate with mercury. The heavy materials, such for instance as platinum when brought into contact with mercury, will, on account of the lateral motion of the riffle, 25 sink through the mass of mercury and being of greater specific gravity will not again rise to the surface and is thus saved.

Another feature in connection with the 30 use of mercury is that by reason of its greater specific gravity, it will always lie under sand, and when the riffle or table is in motion no sand will pack in the riffle on account of the sustaining power of the 35 mercury, and the natural tendency of the sand will be to slip off of the surface of the mercury over the riffle slat. In this connection, attention is called to the fact that the use of mercury prevents the sand from 40 packing in the riffles. When the sand packs in the riffles, the efficiency of the riffle is destroyed and no "values" are retained, whereas in my construction when the bed is in motion, the vibrated mass of mercury collects and retains all the "values" while the 45 sands pass over it without any packing effect.

When my invention is to be used for the recovery of gold only, mercury is not employed and the riffle is formed on a traveling 50 belt moving intermittently in a longitudinal direction by means of the gear 17, pinion 19 and cam 20, while the belt is given a steady, lateral vibration, while the sand, ore, gravel and water are being discharged 55 from the chute 26 onto the belt. The next movement of the riffle longitudinally carries the partially concentrated material back of and away from the feeding point of the chute 26 to a point adjacent to the water 60 nozzle 27, where additional water is applied, thus giving the material a second washing, the belt being laterally reciprocated. The next longitudinal movement of the belt brings the material in position adjacent the 65 water nozzle 28, where the material is again

treated and given a further washing. These movements and the subsequent washings may be continued as long as desired, the result being a clean concentrate at the head of the table or point of discharge and prevents 70 the necessity of ceasing operations for the purpose of cleaning the riffles.

The falling of the ore or sand vertically from the top of the riffle to the bed of the same, and the subsequent washing over the 75 flat or inclined space, causes separation of "values" from the sands by reason of the lateral motion of the table or riffle at right angles to the flow of the water carrying the sand, and its separation by specific gravity. 80

If my riffle inclined upstream (being the opposite to placer and dredger mining practice) should be stationary, all gold would be washed over and lost, but on account of the peculiar effect of the combined movement of 85 the riffle and the water being at right angles to each other, practically all "values," no matter how small the particles may be, are, as above explained, washed under the overhang riffle and are thus saved.

In putting my invention into practice, it is not necessary to erect an especially designed plant, because the riffles may be readily applied to gold dredgers of present 90 construction by making shaking tables of 95 their riffle tables and applying riffles with the inclined side upstream; or in hydraulic and sluice box practice by giving one or more sluice boxes a lateral motion and placing the improved riffle bar as above described.

The specific construction of the means illustrated in the drawing for giving the riffle the lateral reciprocations and the intermittent longitudinal movement may be 105 varied at will, without departing from the spirit of my invention.

I claim:—

1. A riffle provided with a continuous flat bottom, straight, transverse slats thereon, 110 each slat having an undercut face presented upstream, a trap pocket at the bottom of said face formed in the inclined bottom between the slats.

2. A riffle having a continuous flat bottom 115 member provided with straight transverse slats secured to said bottom, each slat having an undercut front face presented upstream, a filling piece with an inclined upper surface also attached to said bottom and extending 120 from the rear face of one slat part-way toward the front face of the next so as to form a trap pocket at the bottom of said front face.

3. A gravel washing machine having an 125 inclined, movable riffle with a flush faced, continuous bottom, transverse slats on the bottom each having a perpendicular rear face and a front face forwardly inclined relative to said bottom, the inclined face 130

being presented upstream a step being provided on the bottom between each pair of slats, and means to reciprocate the riffle laterally.

- 5 4. A gravel washing machine having an inclined, movable riffle with a flush faced continuous bottom provided with a series of steps, transverse slats on the bottom each having a perpendicular rear face and a front 10 face forwardly inclined relative to said bot-

tom, the inclined face being presented upstream and forming a pocket with the step, and means to reciprocate the riffle laterally.

The foregoing specification signed at Sacramento, California, this 17th day of 15 June, 1914.

JAMES B. GIFFEN.
